HARNESS-CONTROL MECHANISM FOR PATTERN WEAVING

Application filed March 23, 1928. Serial No. 264,204.

This invention relates to loom harness control mechanism and aims, among other objects, to provide a relatively simple and relatively cheap attachment to cooperate with one or more treadles of a plain loom to produce many of the same pattern weaves as those heretofore produced by the expensive and complicated dobby pattern heads.

In the accompanying drawing:

10 Fig. 1 is a fragmentary side elevation showing one embodiment of the attachment applied to a multiple treadle loom;

Fig. 2 is a fragmentary top plan of the attachment shown in Fig. 1;

15 Fig. 3 is a sectional view taken on the line 3—3 of Fig. 2;

Fig. 4 is a front elevation showing a pair of pattern chains, parts being omitted;

20 Fig. 5 is a sectional view taken on the line 5—5 of Fig. 3; and

Figs. 6 and 7 are detail views of a brake wheel and a pawl and ratchet shown in Fig. 5.

Referring particularly to the drawing, the selected embodiment of the attachment is shown by way of illustration as being applied to a plain loom 10 having a plurality of treadles 11, 12 and 13 adapted to be actuated by the usual cams 14 and connected to harnesses 15, 16, 17 and 18 in a well known manner. It will be understood however that the device is adapted to be applied to a loom having one or more such treadles and harnesses; but herein, the control mechanism cooperates with two treadles 11 and 12 connected to the harnesses 15, 16 and 17, the treadle 11 being applied to a double harness in a manner well known in the art.

To produce the ordinary pattern weaves such as plain looms are capable of making, it is understood that two or more harnesses must be held periodically inactive; that is to say the cam operating mechanism must be periodically disabled automatically according to the desired pattern. Herein, this is accomplished by pattern controlled mechanism arranged to hold the treadles 11 and 12 inactive or out of engagement at intervals with their respective cams 14. Referring to Fig. 1, the treadle 11 is there shown as being down so that the high part of the cam will not

strike it. The connections between the harnesses and treadles will be such that the inactive harnesses will support their respective warp threads in the upper or lower shed.

In the present example, the attachment includes a pair of rockable latch levers (Figs. 2 and 5) having wedge shaped latch members 19 on their faces arranged to be swung over the ends of the treadles, being aligned with them and mounted to swing in the same vertical planes as the treadles. The upper ends of the latch levers are shown as being pivotally mounted on a common shaft 20 secured to a bracket in the form of a U-shaped frame 21 which is attached to the loom frame.

To control the latch levers a pair of pattern chains 22 of well known design are mounted on sprocket wheels 23 secured directly behind each lever on a common rotatable shaft 24 and the levers have rearwardly projecting arms 25 presenting anti-friction rollers 26 adapted to engage the chain links, the arrangement being such that, when the riser links on a chain engage the roller, the latch lever will be disengaged from its treadle as shown in Fig. 3, and when these links have passed under the roller, the latch lever will swing to the right as viewed in Fig. 1 to lock the treadle. The levers are shown as being adapted to swing to locking position by gravity by reason of their angular positions. That is to say, the levers will naturally swing to their vertical positions aided by the weight of the arms 25.

The pattern sprocket wheels 23 are adapted to be rotated step by step in proper timed relation with the loom. To this end, the shaft 24 is shown as being journaled in both arms of the U-shaped frame and has a ratchet wheel 27 secured to it between the arms (Figs. 5 and 7) and the pawl 28 for operating ratchet is shown as being connected by appropriate means to be actuated by a cam 29 on a shaft 30 of the loom (Fig. 1).

Also, on the shaft 24, between the arms of the frame 21, there is shown a check wheel 31 having notches 32 for a roller 33 mounted on a pivoted arm 34 to which a tension spring 35 is connected so that the roller will check the rotation of the shaft after each impulse.

given to it by the ratchet (Figs. 3, 5 and 6).

In the operation of the mechanism to control the two treadles 11 and 12 and their connected harnesses, it will be understood that the latch levers 18 will engage the ends of these treadles periodically according to the particular pattern link arrangement on the pattern chains which may be varied to produce various combinations of striped and checked weaves. While the treadles are held inactive or are disabled, the connected harnesses will each throw its respective warp threads in the top or bottom shed, depending on the desired connection between the harnesses and the treadles. Thus, the sheds will be open for the filling picks and the warp threads will be floated and, while they are released to be actuated by their respective cams, the harnesses will produce plain weaves. When the control mechanism is applied to a loom having a single treadle to which is connected a double harness such as the harnesses 15 and 16 shown in Fig. 1, it will produce a corded fabric or dimity. Moreover, it is understood that any of the treadles may be permanently disabled by simply disengaging them from their harnesses and dropping them to the floor or out of the path of their cams.

From the foregoing description it will be seen that the improved control mechanism is very simple and can be made very cheaply. It is also applicable to plain looms without requiring any modification of the treadles and their associated mechanism. The whole thing may be attached to the frame of a loom and is capable of controlling as many harnesses as may be required for ordinary pattern weaving, it being only necessary to increase the number of latch levers and pattern chains. All of the parts are easily replaceable without excessive cost and can be installed by unskilled laborers. Further, the cost of the entire attachment installed on a loom is only a small fraction of the cost of the expensive and complicated dobby head attachments.

Obviously the present invention is not restricted to the particular embodiment thereof herein shown and described. Moreover, it is not indispensable that all the features of the invention be used conjointly, since they may be employed advantageously in various combinations and sub-combinations.

What is claimed is:

1. In combination with a loom of the character described, a plurality of adjacent cam operated treadles connected to the harnesses thereof below the lower ends of the harnesses; mechanism for controlling the operation of the treadles to produce pattern weaves including pattern controlled latch means periodically engaging the end of one of the treadles to hold it out of engagement

with its cam while the other treadles are being operated.

2. In combination with a plurality of adjacent treadles of a plain loom, pattern controlled latch mechanism constructed and arranged directly to engage and hold one of the treadles inactive periodically while the other treadles are being operated; and actuating means for the pattern mechanism.

3. In combination with a treadle of a plain loom, pattern controlled mechanism adjacent to the end of the treadle including a swinging latch lever periodically movable into and out of engagement with the free end of the treadle; a pattern chain cooperating with the latch lever to effect such movements; and means to drive the pattern chain in proper timed relation.

4. A pattern control attachment for plain looms comprising, in combination, a frame member adapted to be connected to the loom frame; a counterweighted latch lever pivotally connected to the frame member and adapted to be moved into and out of engagement with the extreme end of a treadle; an operating arm for the latch lever projecting rearwardly of its pivotal connection; and a pattern chain cooperating with the operating arm and connected to be driven in proper timed relation.

5. A pattern control attachment for plain looms comprising, in combination, a frame member adapted to be connected to the loom frame; a latch lever pivotally connected to the frame member and adapted to be moved into and out of engagement with the end of a treadle; an operating arm integral with the latch lever projecting rearwardly of its pivotal connection; a pattern chain cooperating with the operating arm and connected to be driven in proper timed relation; and an anti-friction roller on said operating arm adapted to engage said pattern chain.

6. A pattern control attachment for plain loom comprising, in combination, a substantially U-shaped frame member adapted to be attached to the loom frame adjacent to the ends of the loom treadles; a plurality of latch levers pivotally connected to the frame member above the ends of the treadles and arranged side by side; operating arms projecting from the upper ends of the latch levers; pattern chains arranged side by side behind and cooperating with the respective operating arms; sprocket wheels for the pattern chains rotatably mounted on said frame member; a common shaft for driving said sprocket wheels; pawl and ratchet mechanism operatively connected to a shaft of the loom to drive the shaft and said sprocket wheels; and spring check means connected to check the rotation of the shaft after it is actuated by the pawl and ratchet.

7. In combination with a plain loom having a plurality of harnesses and a plurality

of adjacent treadles, pattern controlled latch mechanism arranged adjacent to the free ends of the treadles and operable selectively and periodically to engage some of the treadles and hold them inactive while the other treadles not so engaged are operating.

In testimony, that I claim the foregoing as my own, I have hereto affixed my signature.
